UNITED STATES PATENT OFFICE.

GEORGE K. MORTON, OF ST. THOMAS, CANADA.

WALLET.

SPECIFICATION forming part of Letters Patent No. 479,655, dated July 26, 1892.

Application filed November 27, 1891. Serial No. 413,279. (No model.)

To all whom it may concern:

Be it known that I, GEORGE K. MORTON, of St. Thomas, Ontario, Dominion of Canada, have invented a new and improved Wallet, 5 of which the following is a full, clear, and exact description.

The object of the invention is to provide a cheap and efficient wallet suitable for the carrying of papers, bank-bills, and the like 10 which will involve a minimum amount of material in its manufacture and which, further, will be neat, light, and less bulky than the ordinary wallet and the contents of which may be inspected or removed with convenience and dispatch.

The invention consists in the novel construction hereinafter described, and defined in the claim.

Reference is to be had to the accompanying 20 drawings, forming a part of this specification, in which similar letters of reference indicate corresponding parts in both the figures.

Figure 1 is a perspective view of a wallet made in accordance with my invention and 25 showing the same closed, and Fig. 2 is a vertical section showing the wallet open.

The wallet A in the form shown is fashioned to form a single pocket only with one fastening, though more pockets and fastenings 30 may be provided, if desired, and it is made in a single piece, its sides a a being continuous and sewed or otherwise secured together at each end, as at b. The material employed may be leather, paper, or canvas or 35 other fabric, as may be preferred, with light strong linings, if necessary. The sides a are free from flaps, straps, and elastics, and they terminate in the same horizontal plane at the top, whereby they form an opening c, which 40 is directly in line with the interior of the wallet whether the latter is closed or open, and each side contains a suitable stiffening e e, through which the fasteners d d' are attached, which add strength and assist in disengaging 45 the fasteners.

To the inner surface of each side a a fastening devices d d' are secured, adapted to engage each other, d indicating a ball, and d' a

socket adapted to receive and hold the ball, the two forming an ordinary ball-and-socket 50 fastening, the members of which engage or lock by simply pressing the sides of the wallet together.

When engaged or locked, the fastening devices form a stop which extends transversely 55 across the interior of the wallet, across and outside of the papers or bills in the latter, and serve to retain such papers or bills, while at the same time a direct opening c is afforded at all times in line with the interior 60 of the wallet. The opening thus provided permits a ready inspection of the contents of the wallet without disengaging the fastening devices, as the sides may be simply flexed outward at each side of the fastening; also, 65 the opening permits a ready entrance of one's fingers to the interior at either side of the fastening for the purpose of pressing the sides apart and, with the assistance of the stiffening e e, quickly disengage such fastening. Further, the simple movement of entering one's fingers between the sides and slightly pressing the same apart both serves to disengage the fastening and to grasp either side for holding the wallet open with one 70 hand while employing the other in the inspection or removal of the contents, the opening of the wallet and the removal or inspection of or addition to its contents and again closing and locking the same being thus more 75 conveniently effected than is possible with wallets of the ordinary form.

The wallet, it will be seen, is light, neat, of economical construction, and more convenient than others, while affording a secure receptacle for carrying papers and the like.

Having thus described my invention, what I claim as new, and desire to secure by Letters Patent, is—

As a new article of manufacture, the here- 90 in-described wallet, closed at the bottom and ends and open at the top, the sides being flexible and free from flaps and having fastening devices held thereto at the inner surface of each near the top, said fastenings be- 95 ing adapted to engage each other and extend-

ing when closed transversely across the interior of the wallet, thus forming a stop for preventing outward movement of the contents of the wallet, the opening at either side 5 of the fastening being directly in line with the interior of the wallet, affording inspection of the contents thereof and permitting entrance of one's fingers in a direct line to the

interior for the ready disengagement of the fastening devices while holding securely with the same hand, substantially as described.

GEO. K. MORTON.
